ABSTRACT

A disposable cartridge assembly for use with a paint spray gun is disclosed, being made out of an inexpensive material, such as plastic, wherein the paint flows into the cartridge assembly and is sucked out of the tip of the cartridge assembly by the force of pressurized air flowing around the cartridge assembly and past the cartridge assembly fluid spray tip opening, thereby atomizing the paint, allowing for an even application of the paint onto a working surface, such as an automobile body. The inexpensive material allows the cartridge to be disposed of after use, rather than cleaned. Further, keeping the paint within the cartridge assembly and away from any inner workings of the paint spray gun reduces or eliminates the need to clean the spray gun after use.

FIG. 1

FIG. 2

DISPOSABLE SPRAY GUN CARTRIDGE

BACKGROUND OF THE INVENTION

I. Field of the Invention

This invention relates to improvements to a hand-held spray gun, specifically designed to be used with a cartridge assembly, such as those used for applying paint, and more particularly to the disposability of the spray gun cartridge.

II. Discussion of the Prior Art

Spray guns are widely used in painting applications where even application of paint is required over fairly wide areas, such as motor vehicles when painting a vehicle following repair after an accident. Typically, in spray guns, the liquid is contained in a reservoir attached to the spray gun from which the liquid is fed to a spray nozzle. At the spray nozzle, compressed air atomizes the liquid into a spray which is then applied to the surface being painted. The liquid may be gravity fed, suction fed or even pressure fed by an air bleed line to the reservoir from the compressed air line to the spray gun.

Traditionally, paint spray guns and paint spraying equipment must be thoroughly cleaned after each use, and much time is spent properly cleaning the equipment and parts of the spray gun. Solvent costs and the disposable waste generated by cleaning the spray gun add additional expense and waste. The present invention substantially reduces, and may even eliminate, that cost and waste.

Traditional spray guns also have set fluid tip sizes or, if adjustable, must be thoroughly cleaned after each use. The present invention can be made in varying fluid tip sizes depending upon the application or painting project and do not require cleaning after use.

SUMMARY OF THE INVENTION

The present invention provides a spray gun with a disposable cartridge assembly, the cartridge assembly body being a hollow tube structure with an inner and an outer surface area, a reservoir connector, a fluid spray tip and fluid spray tip opening and a cap end opening, and further having a fluid needle, a fluid needle seal, a fluid needle washer, a fluid compression spring, an E-clip and a cap. The cartridge assembly would fit within a typical spray gun and be easily removable for disposal after its use. The cartridge assembly could also have various shapes and sizes to fit within a variety of spray guns. A reservoir would deliver liquid, such as paint, a chemical, a stain, a varnish or other sprayable liquid to the cartridge assembly through a reservoir connector and into the hollow body of the cartridge assembly. Pressurized air would flow into the spray gun, around the cartridge assembly and out the spray tip of the spray gun, thereby forcibly siphoning the liquid out of the cartridge assembly and atomizing the liquid for application onto the surface being sprayed. The reservoir holding the liquid could be attached to the cartridge assembly by the reservoir connector inlet opening, or the liquid could be delivered by tubing or some other means to the cartridge assembly. The reservoir connector inlet opening configuration would vary to match the particular type of reservoir or fluid hose from which the liquid would enter the cartridge assembly. The cartridge assembly body, fluid needle and cap could be made of a variety of inexpensive materials, such as plastic, metal, an alloy or some sturdy recycled material.

BRIEF DESCRIPTION OF THE DRAWINGS

FIG. 1 is a cut-away view of the cartridge assembly; FIG. 2 is an exploded view of the cartridge assembly; and

FIG. 3 is a cut-away view of a typical spray gun with the cartridge assembly contained therein.

DETAILED DESCRIPTION OF THE DRAWINGS

5

Referring to FIG. 1, the cartridge assembly 1 is shown cut in half lengthwise. The cartridge assembly 1 comprises a body 2, an outer surface 3, an inner surface 4, a tapered fluid spray tip 5, a fluid spray tip opening 6 and a connector inlet opening 7.

Referring now to FIG. 2, the cartridge assembly 1 is shown in exploded view, further comprising an E-clip 8, a fluid compression spring 9, a fluid needle washer 10, a fluid needle seal 11, a fluid cartridge end cap 12 and a fluid needle 13. The cartridge end cap 12 further comprises a fitting end 14 and a needle adjustment end 15. The cartridge end cap 12 further comprises a bore 16 from the fitting end 14 to the needle adjustment end 15. The bore 16 is of sufficient diameter to allow the fluid needle 13 to slide through the cartridge end cap 12.

Referring still to FIG. 2, the fluid needle 13 comprises a tapered spray tip end 17, a control end 18 and an annular groove 19 about midway between the tapered spray tip end 17 and the control end 18. The fluid needle 13 has a diameter slightly smaller than the diameter of the cartridge end cap bore 16, such that the fluid needle 17 can slide within the bore 16 through the fluid cartridge end cap 12. The control end 18 has a diameter larger than the cap bore 16 to prevent the fluid needle 13 from passing entirely through the fluid cartridge end cap 12. In operation, the fluid needle 13 slides through the fluid cartridge end cap 12, tapered spray tip end 17 first through the needle adjustment end 18, the fluid needle seal 11 is situated around the fluid needle 13 and fits snugly inside the fluid cartridge end cap 12, thereby preventing the flow of liquid out through the bore 16, after which the fluid needle washer 10 is placed on the fluid needle 13, then the fluid compression spring 9 is placed on the fluid needle 13, and the E-clip 8 is fastened around the fluid needle 13 in the annular groove 19, thereby preventing the fluid compression spring 9 and the fluid needle washer 10 from sliding off the fluid needle 13. The fluid cartridge end cap 12 is then attached to the body 2 by inserting the fitting end 14 into the body 2 and securing the fluid end cap 12 to the body 2 with adhesive means. Friction can also hold the fluid end cap 12 onto the body 2 by having the fitting end be of sufficiently large diameter to fit snugly within the inner surface 4 of the body 2.

Referring again to FIG. 1, the cartridge assembly 1 is shown with the fluid needle 13 in its at rest position, wherein the tapered spray tip end 17 of the fluid needle 13 is seated within the fluid spray tip opening 6. While in its at rest position, no liquid can escape the cartridge assembly 1. In operation, the fluid needle 13 would be pulled out slightly from its seated position, thereby allowing liquid to escape through the fluid spray tip opening 6. A reservoir for fluid (not shown) would be attached to the reservoir connector inlet opening 7, allowing liquid to feed into the cartridge assembly 1 by means of gravity.

Referring to FIG. 3, a spray gun 20 is shown with the cartridge assembly 1 in place and the reservoir 28 attached to the reservoir connector inlet opening 7 of the cartridge assembly 1. In operation, the cartridge assembly fits within the barrel 21 of the spray gun 20 with the reservoir connector inlet opening 7 protruding from the barrel 21, such that a seal is formed around the reservoir connector inlet opening 7 to prevent the flow of air out of the barrel 21 around the reservoir connector inlet opening 7. The spray gun 20 comprises a trigger 22 that controls the amount of pressurized air flowing into the barrel 21 of the spray gun 20, a lever assembly 23, an inlet air port 24 and a nozzle 25. The trigger 22 is attached to the lever assembly 23 that actuates the fluid needle 13, mov-

ing the fluid needle 13 from its at rest position, thereby unseating the tapered spray tip end 17 of the fluid needle 13 from the fluid spray tip opening 6. Pressurized air flows into the spray gun 20 through an inlet air port 24 and flows through the spray gun 20, exiting the nozzle 25. The cartridge assembly 1 fits within the barrel 21 of the spray gun 20 such that there exists a space 26 around the cartridge assembly 1, allowing the pressurized air to flow around and past the cartridge assembly 1, exiting at the nozzle 25 of the spray gun 20. As the trigger 22 is pulled, the fluid needle 13 is moved out of its seated at rest position, thereby allowing liquid fed by gravity from the reservoir 28 to the cartridge assembly 1 to escape from the fluid spray tip opening 6 and become atomized by the pressurized air flowing out of the nozzle 25 of the spray gun 20. A fluid adjuster knob 27, movably attached to the spray gun 20, limits the movement of the trigger 22, thereby controlling the amount of pressurized air entering the spray gun 20, which controls the amount of liquid escaping from the cartridge assembly 1. The amount of liquid that is sucked out of the fluid spray tip opening 6 of the cartridge assembly 1 is determined by the flow of pressurized air flowing past the fluid spray tip opening 6. The stronger the flow of pressurized air, the more liquid is sucked out of the fluid spray tip opening 6. The fluid spray tip opening 6 would have a diameter of sufficient size to suit the type of liquid being applied. Thinner liquids would require a smaller diameter fluid spray tip opening 6 while thicker liquids would require a larger diameter fluid spray tip opening 6.

No liquid touches any inner part of the spray gun 20, thus allowing for easy clean up after use. The cartridge assembly 1 and its components can be made of any number of inexpensive materials, such as plastic, thereby allowing the user to dispose of the cartridge assembly 1 after its use, thus substantially reducing or eliminating any cleaning.

This invention has been described herein in considerable detail in order to comply with the patent statutes and to provide those skilled in the art with the information needed to apply the novel principles and to construct and use such specialized components as are required. However, it is to be understood that the invention can be carried out by specifically different equipment and devices, and that various modifications, both as to the equipment and operating procedures, can be accomplished without departing from the scope of the invention itself.

What is claimed is:

1. A spray gun having a body, the spray gun comprising: a device comprising:
  - a removable cartridge assembly sized and dimensioned to be releasably insertable within the spray gun body, the cartridge assembly including:
    - a spray needle having a spray end and a control end;
    - a one piece reservoir for receiving and containing a liquid to be sprayed, the reservoir integrally including:
      - a spray liquid chamber for containing a supply of liquid to be sprayed;
      - a spray opening to permit the liquid to be sprayed to pass out of the reservoir, and
      - an open end opposite the spray opening,
      - an inlet for admitting the liquid to be sprayed into the spray liquid chamber;
    - a biasing element arranged inside the spray liquid chamber and positioned to bias the needle to pass through the spray opening to control flow of the liquid to be sprayed out of the reservoir; and
    - a seal situated between the biasing element and the exterior of the reservoir at the open end opposite the needle opening to prevent flow of fluid out of the reservoir;

an air inlet port; a nozzle; and a chamber disposed within the body, the chamber sized and dimensioned to releasably admit insertion of at least a portion of the cartridge assembly, wherein when the device is inserted into the body of the spray gun, a space is formed between the body of the spray gun and the cartridge assembly allowing pressurized air to flow around and past the cartridge assembly to exit through the nozzle together with the spray liquid from the reservoir.

2. The device of claim 1, wherein the biasing element of the removable cartridge assembly is configured to surround the needle inside of the reservoir.

3. The device of claim 2, wherein the needle further comprises an annular groove arranged between the spray end and the control end.

4. The device of claim 3, wherein the cartridge assembly further includes an e-clip fastened around the needle in the annular groove, and wherein the biasing element is a spring, the e-clip thereby positioned to connect an end of the spring to the needle.

5. The device of claim 1, wherein at least one of the reservoir and the needle are fabricated with plastic.

6. A spray gun having a body, the spray gun comprising: a device comprising:

a removable cartridge assembly sized and dimensioned to be releasably insertable within the spray gun body the cartridge assembly including:

a spray needle having a spray end and a control end; a one piece reservoir for receiving and containing a liquid to be sprayed, the reservoir integrally including:

a spray liquid chamber for containing a supply of liquid to be sprayed;

a spray opening to permit the liquid to be sprayed to pass out of the reservoir, and

an open end opposite the spray opening,

an inlet for admitting the liquid to be sprayed into the spray liquid chamber;

a biasing element arranged inside the spray liquid chamber and positioned to bias the needle to pass through the spray opening to control flow of the liquid to be sprayed out of the reservoir; and

a seal situated between the biasing element and the exterior of the reservoir at the open end opposite the needle opening to prevent flow of fluid out of the reservoir;

an air inlet port;

a nozzle;

a chamber disposed within the body, the chamber sized and dimensioned to releasably admit insertion of at least a portion of the cartridge assembly; and

a trigger connectable to the control end of the needle when the cartridge assembly is inserted into the gun body, the trigger thereby movable to slide the needle within the reservoir and to permit pressurized air to flow through the spray gun body around the inserted cartridge assembly.

7. A spray gun comprising:

a housing including a chamber; a removable cartridge assembly sized and dimensioned to be releasably insertable within the chamber, the cartridge assembly including:

a spray needle having a spray end and a control end;

a one piece reservoir for receiving and containing a liquid to be sprayed, the reservoir integrally including:

a spray liquid chamber for containing a supply of liquid to be sprayed,

- a first opening cooperative with the spray end of the needle to permit the liquid to be sprayed to pass out of the reservoir;
- a second opening opposite the needle opening through which the needle control end passes, and a third opening for admitting the liquid to be sprayed into an interior of the reservoir;
- 5 a biasing element arranged inside the spray liquid chamber and positioned to bias the needle to engage the spray tip opening to control flow of the liquid to be sprayed out of the reservoir; and
- 10 a seal positioned between the biasing element and an exterior of the reservoir at the second opening, the needle passing through the seal.
- a trigger for controlling a position of the needle to thereby control an amount of pressurized air flowable into the spray gun; and
- 15 a lever connected to the trigger and connectable to the control end of the spray needle when the cartridge assembly is inserted into the housing, wherein when the trigger is moved the needle is slid between a rest position wherein the spray end is seated within the spray tip opening, to an active position wherein the spray end is at least partially withdrawn from the spray tip opening thereby allowing liquid to be sprayed to pass through the spray tip opening.
- 8. The spray gun of claim 7, wherein the biasing element is 25 a spring which is connected to the needle and surrounds the needle inside of the reservoir.
- 9. The spray gun of claim 8, wherein the spring is connected to the needle by an e-clip fastened around the needle in within an annular groove.
- 10. The spray gun of claim 7, wherein at least one of the reservoir and the needle are fabricated with plastic.
- 11. The spray gun of claim 7, further including an end cap 30 releaseably positionable within the second opening and including a bore through which the control end of the needle is slideably passable, the seal connected to the bore.
- 12. The spray gun of claim 7, further including a seal 35 positioned to prevent air from flowing out of the spray gun proximate the third opening.

- 13. A spray gun, comprising:
a housing including a chamber;
a removable cartridge assembly sized and dimensioned to be releasably insertable within the chamber, the cartridge assembly including:
a spray needle having a tapered spray end and a control end;
a one piece reservoir for receiving a liquid to be sprayed, the reservoir integrally including:
a spray liquid chamber for containing a supply of liquid to be sprayed,
a first opening cooperative with the spray end of the needle to permit the liquid to be sprayed to pass out of the reservoir,
a second opening at an end opposite the spray opening, through which the needle control end passes, a third opening for admitting the liquid to be sprayed into an interior of the reservoir; and
a biasing element arranged inside the spray liquid chamber and connected to the needle to bias the spray end of the needle towards the first opening;
a lever connectable to the control end of the spray needle when the cartridge assembly is inserted within the housing;
a trigger connected to the lever to slide the spray needle within the reservoir when the cartridge assembly is inserted into the chamber and the control end of the spray needle is connected to the lever and the trigger is moved;
an air passage positioned to admit compressed air from a compressed air inlet to an area adjacent the first opening; a first seal positioned to prevent air from flowing out of the spray gun past the reservoir proximate the third opening; and
a second seal in fluid communication with the reservoir and positioned between the biasing element and an exterior of the reservoir at the second end, the needle passable through the second seal.
